GUN BARREL LOCK

Henry Schirokauer, New York, N. Y., assignor to
Schirgun Corporation, a corporation of Delaware

Application March 24, 1942, Serial No. 436,032

15 Claims.

(Cl. 42—75)

The invention relates to mechanism for locking the gun barrel in the gun frame. While gun barrels generally should be readily demountable it is, of course, important that when the gun is in use the barrel be more or less rigidly locked in place in the frame, so as to be held more or less immovable and properly meet the stress caused by the firing of the gun.

The present invention is not confined to use in any specific type of gun and phases of the invention may be readily adapted and employed in guns of many different characters. For explanatory purposes the invention as applied to one type of gun may be referred to. It may be particularly convenient for this purpose to describe a locking device in an automatic or semi-automatic gun in which there may be mounted in the frame parallel to the gun barrel a cylinder tube in which a cylinder is operated by explosion gases of the gun.

In such an arrangement the gun barrel itself may be seated in a socket in a frame and may be provided with a step or enlarged portion adapted to fit snugly against the frame.

There may be an opening in the frame through which may pass a locking member to engage the barrel. The locking member may have one side engage a side of the opening in the frame. At its other side the locking member may be provided with a seat for engaging the gun barrel. The engagement may preferably be an arc-shaped tapered engagement providing a large surface contact. The seat on the locking member may be tapered or bevelled and may engage a portion or recess in the gun barrel appropriately tapered or bevelled to cooperate therewith or only one surface may be tapered. The arrangement thus will be such that the locking member tends to bind between the edge of the opening in the frame and the gun barrel in such a way as to draw and hold the projection or seat on the gun barrel tightly in place against the frame.

The locking member may be supported, adjusted, operated and held or fastened in any suitable manner. A specific adaptation of the invention may contemplate a U-shaped locking member pivoted between its ends about the piston cylinder, the locking member which may be bevelled or tapered being arranged at one end and the other end being provided with an adjusting means such as a thumb screw, which may bear against the adjacent side of the frame in such a way as to pull and hold the locking member tightly and snugly in contact with the appropriate portions of the opening in the frame and the part of the barrel to be engaged.

In the accompanying drawing is shown one specific embodiment of the invention. Figure 1 is a side elevation of a gun embodying the improved gun barrel lock. Fig. 2 is a fragmentary longitudi-

dinal transverse section on the line 2—2 of Fig. 1 looking in the direction indicated by the arrows. Fig. 3 is a transverse vertical section through the locking mechanism showing it in engaging position. Fig. 4 is a transverse vertical section similar to Fig. 3 showing the locking mechanism in unengaged position. Fig. 5 is a fragmentary enlarged section of the lock engaging portion indicated in Fig. 2 somewhat deformed to emphasize phases. The various figures are made on different scales for the purpose of more clearly indicating the details of the mechanism.

The invention may be employed with guns of various types but has been illustrated in connection with an automatic or semi-automatic gun in which there is a barrel 10 held in the frame 11 which also holds a gas tube 12 which may act as the cylinder for a piston causing the operation of the gun. This mechanism is known in the art and forms no part of the present invention and therefore need not be further described. The cylindrical tube 12 shown is arranged in the casing 11 parallel to the barrel 10. As shown the tube 12 fits in a seat or socket 13 in the frame 11 above the barrel 10 which itself has a seat or socket 13 in the frame 11. On the barrel 10 is a projection shown as a ring 14 which may engage the end of the seat 13 and properly position the barrel in the frame 11. It will be noted that the enlargement 14 is toward the front end of the barrel 10 so that the barrel may be inserted into its seat 13 by being placed therein from the front end of the frame 11.

A slot or aperture 15 is provided in the upper part of the frame 11 so as to expose both the tube 12 and the barrel 10. At this slot there may be rotatably mounted in any suitable manner such as on the tube 12 a barrel locking mechanism 16 which as shown is made more or less U-shaped in form having one depending arm 17 extending outside the frame 11 at which point it is threaded to receive a screw 18 having a knurled head 19. The end of the screw 18 may engage the face of the frame 11 so as to adjust the locking mechanism.

At the slot the barrel 10 is provided with a circumferentially disposed arc-shaped slot 20 which is adjusted to be open on the side of the barrel opposite the screw 18. The rearward edge 50 of the slot 20 may be suitably bevelled as at 21, the taper being inward toward the bottom of the slot 20. The arm 22 of the locking member 16 opposite the arm 17 is more or less arc-shaped but preferably on a radius somewhat larger than the radius of the barrel 10. Preferably the front side 23 of the arm 22 is flat or straight and makes contact with the frame 11 at the front edge of the opening 15. The rear side of the arm 22 may be bevelled or tapered at 24 so as to engage the bevelled wall 21 of the barrel 10. As indicated in Fig. 4 when the screw 18 is unscrewed

the arm 22 may be drawn out of line with the barrel 10 and allow it to be inserted or removed from the frame 11. After the barrel is placed in its seat the screw 18 may be screwed in and as its end engages the frame 11 it will force the bevelled edge 24 of the arm 22 into engagement with the bevelled edge 21 of the barrel slot. This tends to jam the arm 22 between its engagement at 23 with the frame 11 and the bevelled face 21 on the barrel 10. At the same time this action pulls the stop or collar 14 on the barrel snugly into engagement with the front end of the frame 11. This holds or locks the barrel tightly into its seat in the frame so as to resist the tendency to movement caused by the firing of the gun.

In order to make the locking member 16 operate it must be moved toward or from the axis of the barrel. This may be done in a variety of ways. One convenient way of providing for this movement is shown in the drawing, by pivoting the locking member in the frame on the cylinder 12.

The bevelled surface 24 on the arm 22 is arcuate and extended in area so that as the locking member 16 is operated it may readily adjust itself and reach a proper seat on the arcuate bevelled portion 21 of the gun barrel 10. As indicated in Fig. 2 and Fig. 5 the slot 20 in the barrel 10 is somewhat larger than the width of the arm 22 of the lock. The edge of the opening in the frame 11 overhangs the front wall of the slot 20 so that adjustment or wear is taken care of. It will be noted that there is a space between the front edge 23 of the arm 22 and the front edge of the slot 20. Similarly the rear wall 25 of the slot in the frame 11 is spaced away from the rear wall of the arm 17 so that as the members wear adjustment is possible and the parts will not bind out of locking position. This arrangement not only allows for continued operation of the locking mechanism if there should be wear in the parts but also provides for tolerance in manufacture so that slight inaccuracies which may be unavoidable may not interfere with the effective operation of the device. It will be noted that the contact of the bevelled surfaces 21 and 24 is about 90° against the direction of the forces which try to move the barrel out on firing the gun. This may be a most convenient arrangement but it is not essential to all phases of the invention. It will be noted that the locking is here effected by the engagement of two bevelled surfaces 21 and 24. This may be an advantage and may provide especially effective locking but is not essential since locking might be carried out if one or the other of the surfaces 21 and 24 were straight instead of bevelled so that there might be a point or line wedging contact between the members instead of the surface contact illustrated.

It will be noted that the bevelled edge 24 of the arm 22 is arc-shaped and on a radius which may be somewhat larger than the radius of the barrel 10 and also larger than the radius of the bottom of the slot 20 in the barrel. This arrangement may not be essential but may be particularly desirable since it affords easy insertion and withdrawal of the barrel when the arm 22 is moved only a slight distance so as not to interfere with the barrel. At the same time this arrangement by this variation of radius of the arcs allows a good seat and a large face contact between the bevelled portions 21 and 24. The

actual arrangement illustrated in which the various arcs may be of different radii and drawn from different centers may be advantageous but is not essential to the present invention. It will be noted, however, that in Fig. 3 the center of the arc of the arm 22 may be to the right of the center of the barrel 10, while in the unengaged position indicated in Fig. 4 the center of the arc of the arm 22 may be to the left of the center of the barrel 10.

It will be noted that when released the locking mechanism 16 may be held from swinging too far out of position by a stop 26 which may be a continuous portion of the frame 11 bridging the slot 15 in the frame.

The mountings and the operation of the device as well as the relative sizes, proportions and arrangement may be varied within wide limits without departing from the present invention set out in the appended claims.

I claim as my invention:

1. In a gun, a frame, a barrel in the frame, a projection on the barrel at the frame entrance, an arcuate recess in the barrel, a flat wall on the front side of the recess, a tapered wall on the rear side of the recess, a cylindrical tube in the frame parallel to the barrel, a locking member having two arms and pivoted between the arms on the cylindrical tube, an arcuate tapered surface on one side of one arm, a flat surface on the other side of the last mentioned arm, the last mentioned arm being adapted and arranged to extend through the frame and into the arcuate recess in the barrel, and a bolt threaded through the other arm and engaging the frame so as to cause the tapered side of the first mentioned arm to engage the tapered wall of the barrel recess to force the projection on the barrel into close engagement with the frame and also force the flat side of the first mentioned arm into close engagement with the frame.

2. In a gun, a frame, a barrel in the frame, a projection on the barrel at the frame entrance, an arcuate recess in the barrel, a tapered wall on the rear side of the recess, a locking member having two arms and pivoted between the arms on the frame, an arcuate tapered surface on one side of one arm, a flat surface on the other side of the last mentioned arm, the last mentioned arm being adapted and arranged to extend through the frame and into the arcuate recess in the barrel, and a bolt threaded through the other arm and engaging the frame so as to cause the tapered side of the first mentioned arm to engage the tapered wall of the barrel recess to force the projection on the barrel into close engagement with the frame and also force the flat side of the first mentioned arm into close engagement with the frame.

3. In a gun, a frame, a barrel in the frame, a projection on the barrel at the frame entrance, a recess in the barrel, a tapered wall on the rear side of the recess, a locking member having two arms and pivoted between the arms on the frame, a tapered surface on one side of one arm, the last mentioned arm being adapted and arranged to extend through the frame and into the recess in the barrel, and a bolt threaded through the other arm and engaging the frame so as to cause the tapered side of the first mentioned arm to engage the tapered wall of the barrel recess to force the projection on the barrel into close engagement with the frame and also force the other side of

the first mentioned arm into close engagement with the frame.

4. In a gun, a frame, a barrel in the frame, a stop for the barrel, a recess in the barrel, a tapered wall on the rear side of the recess, a locking member having two arms and pivoted between the arms on the frame, a tapered surface on one side of one arm, the last mentioned arm being adapted and arranged to extend through the frame and into the recess in the barrel, and means on the other arm to cause the tapered side of the first mentioned arm to engage the tapered wall of the barrel recess so as to force the other side of the first mentioned arm into close engagement with the frame.

5. In a gun, a frame, a barrel in the frame, a stop for the barrel, a recess in the barrel, a tapered wall on the rear side of the recess, a cylindrical tube in the frame parallel to the barrel, a locking member having two arms and pivoted between the arms on the frame, a tapered surface on one side of one arm, the last mentioned arm being adapted and arranged to extend through an opening in the frame out of contact with the rear wall of the opening and into the recess in the barrel but out of contact with its front wall, and means on the other arm to cause the tapered side of the first mentioned arm to engage the tapered wall of the barrel recess so as to force the other side of the first mentioned arm into close engagement with the frame.

6. In a gun, a frame having an aperture therein, a barrel in the frame, a stop for the frame on the barrel, a bevelled surface on the barrel adjacent the aperture, a locking member pivoted in the frame and swinging transversely of the barrel adapted to enter the aperture, a bevelled surface on the locking member engaging the bevelled surface on the barrel to jam the locking member between the bevelled surface and the side of the aperture and hold the frame against its stop, and means for holding the members in engagement.

7. In a gun, a frame having an aperture therein, a barrel in the frame, a stop for the frame on the barrel, a bevelled surface on the barrel adjacent the aperture, a locking member pivoted in the frame and swinging transversely of the barrel adapted to enter the aperture, a bevelled surface on the locking member engaging the bevelled surface on the barrel to jam the locking member between the bevelled surface and the other side of the aperture and hold the frame against its stop, and means for holding the members in engagement.

8. In a gun, a frame having an aperture therein, a barrel in the frame, a stop for the barrel, a bevelled surface on the barrel adjacent the aperture, a locking member pivoted in the frame and swinging transversely of the barrel adapted to enter the aperture, a bevelled surface on the locking member engaging the bevelled surface on the barrel to jam the locking member between the bevelled surface and the side of the aperture to draw the stop against the frame, and means for holding the members in engagement.

9. In a gun, a frame, a barrel in the frame, a stop for the barrel, an arcuate bevelled surface on the barrel, a locking member pivoted in the frame and swinging transversely of the barrel to engage the frame, an arcuate bevelled surface on the locking member, and means to force the bevelled surfaces into wedging contact adapted and arranged to lock the barrel in the frame and the frame against the stop.

10. In a gun, a frame, a barrel in the frame, a stop for the barrel, a locking member pivoted in the frame and swinging transversely of the barrel to engage the frame, a seat in the barrel for the locking member, engaging faces in the locking member and in the seat, an arcuate bevelled surface in at least one of the engaging faces, and means to force the engaging faces into wedging contact adapted and arranged to lock the barrel in the frame and the frame against the stop.
11. In a gun, a frame, a barrel removably mounted in the frame, a stop for the barrel, a lock for holding the barrel and the frame in position comprising a U-shaped member mounted in a slot in the frame about the barrel adapted to swing transversely of the barrel, an adjusting member at one end of the U-shaped member adapted to rest against the frame, a bevelled surface on the other end of the U-shaped member, and a correspondingly bevelled groove in the side of the barrel opposite the adjusting member to receive the bevelled surface at the end of the U-shaped member when the adjusting member engages the frame and arranged and adapted to draw the frame against the stop.
12. In a gun, a frame, a barrel removably mounted in the frame, a stop on the barrel near the end adapted to fit against the frame a groove on the barrel spaced from the stop, a lock for the barrel comprising a U-shaped locking member, a slot in the frame to receive the locking member and hold it about the barrel, an adjusting member on one end of the U-shaped member, a bevelled surface on the opposite end of the U-shaped member and means for operating the adjusting means to cause the bevelled surfaces to form a close wedge in the groove of the barrel to force the barrel rearward of the frame and bring the stop on the barrel in close contact with the frame.
13. In a gun, a frame, a barrel in the frame, a stop for the barrel, a transverse slot in the barrel, a transversely moving locking member narrower than the slot mounted on the frame, an aperture in the frame wider than the locking member and in register with the slot, and means for forcing the locking member into the slot and aperture and into contact with the forward wall of the aperture and into wedging contact with the rear wall of the slot and arranged and adapted to draw the frame against the stop.
14. In a gun, a frame, a barrel in the frame, a stop for the barrel, a transverse slot in the barrel, a transversely moving locking member narrower than the slot mounted on the frame, an aperture in the frame wider than the locking member, engaging seats on the locking member and the slot at least one of which is arc-shaped and tapered, and means for forcing the locking member transversely of the barrel and into contact with the forward wall of the aperture and the rear wall of the slot and arranged and adapted to draw the frame against the stop.
15. In a gun, a frame, a barrel in the frame, a recess in the barrel, a tapered wall on the rear side of the recess, a locking member pivoted on the frame adapted and arranged to extend through the frame and into the recess in the barrel, a tapered surface on one side of the locking member, and means to cause the tapered side to engage the tapered wall so as to force the other side of the locking member into close engagement with the frame and draw the frame into contact with the stop.
